CLAIM

The ornamental design for an ergonomic twin baby carrier, as shown and described.

DESCRIPTION

FIG. 1 is a perspective view of an ergonomic twin baby carrier showing the rear, top and right sides, in a first embodiment.

FIG. 2 is a right side view of the ergonomic twin baby carrier of FIG. 1.

FIG. 3 is a left side view of the ergonomic twin baby carrier of FIG. 1.

FIG. 4 is a rear side view of the ergonomic twin baby carrier of FIG. 1.

FIG. 5 is a front side view of the ergonomic twin baby carrier of FIG. 1.

FIG. 6 is a top view of the ergonomic twin baby carrier of FIG. 1.

FIG. 7 is a bottom view of the ergonomic twin baby carrier of FIG. 1.

FIG. 8 is a perspective view of the ergonomic twin baby carrier of FIG. 1 showing the front, top and right sides, with additional environment and in an alternate state.

FIG. 9 is a right side view of the ergonomic twin baby carrier of FIG. 1 and in a second alternate state.

FIG. 10 is a left side view of the ergonomic twin baby carrier of FIG. 1 and in a third alternate state.

FIG. 11 is a right side view of the ergonomic twin baby carrier of FIG. 1 and in a fourth alternate state; and, FIG. 12 is a right side view of the ergonomic twin baby carrier of FIG. 1 and in a fifth alternate state.

The broken lines depict portions of the article that form no part of the claimed design.

1 Claim, 7 Drawing Sheets
